[57] **ABSTRACT**

A variable attenuator for use in a radiation beam path comprising at least one obturating element which element is capable of varying its physical form, whereby according to the degree of such variation the element may of itself, or in combination with other elements, attenuate a radiation beam path in which it is placed to a greater or lesser degree, there being further provided control means for providing gradual variation in the physical form of the element.

ADJUSTABLE-SPRING ATTENUATOR FOR RADIATED BEAMS

FIELD OF THE INVENTION

This invention relates to attenuators for radiation beams such as optical beams.

BACKGROUND OF THE INVENTION

Many optical instruments require attenuating devices capable of giving precise control of varying attenuation of an optical beam path. Attenuators for instruments such as gas analysers, for example, have generally involved the use of wedge combs or shutters placed in the optical beam, calling for carriages and guides manufactured to a high degree of accuracy. Previously known precision attenuators have, therefore, tended to be costly and somewhat complex.

SUMMARY OF THE INVENTION

The object of the present invention is to provide a variable attenuator for the purpose described which, whilst capable of precise adjustment, is both of simple construction and inexpensive.

According to the present invention a variable attenuator for use in a radiation beam path comprises at least one obturating element which element is capable of varying its physical form, whereby according to the degree of such variation the element may of itself, or in combination with other elements, attenuate a radiation beam path in which it is placed to a greater or lesser degree, there being further provided control means for producing gradual variation in the physical form of the element.

In the preferred form of the invention, a variable attenuator includes a helical coil spring which is placed in the beam path to be attenuated, the coil density of the spring in the beam path being controllable by means of a spring take-up arrangement which may be automatically or hand-operated. The spring is preferably placed across the full height or full width of the beam to be attenuated and variation of the spring coil density alters the number of turns met by the beam thus altering the degree of obscuration.

The spring may be a compression spring but is preferably an extension spring continuously under tension for all settings of the attenuator. It is also possible, however, to use a coil spring varying between compression and extension over the operating range of the attenuator.

One embodiment of the invention will now be described with reference to the accompanying drawing in which:

DESCRIPTION OF THE DRAWING

FIG. 1 shows a simple perspective view of an optical beam path attenuator according to the present invention.

FIG. 2 shows a sectional front elevation of a spring take-up arrangement of the attenuator shown in FIG. 1, and

FIG. 3 shows a side elevation of the spring take-up arrangement shown in FIGS. 1 and 2.

DESCRIPTION OF A PREFERRED EMBODIMENT

Referring to the drawing, the attenuator shown comprises a spring wire coil 1 supported by a bracket 2 such that several of the spring coils may interrupt a light beam indicated by arrow 'A'.

The coil 1 is fixed at its lower end to bracket 2 by screws 3, the upper end of the coil being arranged to wind onto the cylinder 4 of a coil take-up arrangement.

- 10 The latter arrangement comprises, in addition to cylinder 4, a knurled operating knob 5, a shaft 6 and a transverse pin 7, in fixed relationship to one another and arranged to rotate together by means of the shaft 6 being mounted in a hole in an end wall at the top of cylinder 4. 15 The extreme upper end of the coil is fixed between the cylinder 4 and the bracket 2, cylinder 4 being rigidly held by the bracket.

The arrangement shown enables the number of turns of coil 1 passing through a fixed beam area, or 'path', 20 to be varied by turning the knob 5 and thus taking up a greater or lesser number of the coil turns on to cylinder 4.

Typical dimensions for the attenuator shown are as follows:

25

Beam 'patch' size:	25 x 40 mm rectangle.
Normal coil length:	5" approximately.
Distance from bottom fixing screws to pin 7:	4½".
Diameter of wire forming coil:	12½ thousandths of an inch.
Diameter of coil take-up cylinder:	1½".

The attenuator described, in addition to being generally mechanically simple and robust, is particularly suitable for use in locations subject to vibration since, although the coil may vibrate in such circumstances, the overall attenuating effect of the coil remains constant to a surprisingly high degree.

40 The invention is not limited to the use of coil springs as attenuating elements. Alternative forms may comprise, for example, a plurality of elements of leaf-spring shape, or a deformable strip of zig-zag configuration. A further possible embodiment may employ a body of material capable of transmitting radiation, the change in form of the body being arranged to alter the path length of radiation through the body, and thus vary the attenuation of the beam.

45 It will be appreciated that the invention is not limited to attenuators for optical beams but may also be applied to attenuators for alternative forms of radiation, for example, infra-red radiation.

I claim:

1. A variable attenuator for use in a radiated beam path comprising at least one obturating element which element is capable of varying its physical form, whereby according to the degree of such variation the element may of itself, or in combination with other elements, attenuate a radiated beam path in which it is placed to a greater or lesser degree; and control means operatively connected to said obturating element for providing gradual variation in the physical form of the element, said obturating element comprising an elongated, cylindrical helical coil spring for location with the longitudinal axis of the coil spring normal to the beam path being attenuated, the coil density of the spring in the beam path being substantially infinitely controllable within the physical distortion limits of the

cylindrical, helical coil spring, the spring defining a cylinder in elevation for disposition across the full height or width of the beam to be attenuated and variations of the spring coil density causing an alteration in the number of turns of the spring met by the beam and thus altering the degree of the obscuration, said coil spring being fixedly anchored at one end, and said control means comprising a cylinder element connected axially to the other end of the coil spring, said coil spring being continuously under stress, and means for adjustably rotating the cylinder to impose torque on the individual helical coils of the spring for altering the diameter of the cylindrical coil and the spacing between adjacent helical coils of the spring.

2. A variable attenuator for use in combination with a radiated beam for adjustably-attenuating the beam path in relation to the physical extension or detention of an obturating element comprising:

support means having spaced portions defining the general area for which a radiated beam to be attenuated will pass;
at least one, elongated, axially-deformable obturating element anchored between said support portions in intercepting relation to said area through which the beam will pass; and
means for adjusting the axial length of said obturating

element axially between said spaced support portions, said obturating element comprising a cylindrical, helical coil spring continuously stressed between said space support portions during all positions of adjustment.

3. The variable attenuator as claimed in claim 2 in which said cylindrical, helical coil spring is terminally anchored at one end on one support portion, said other support portion including a cylindrical drum telescopically and fixedly connected to the other end of said helical coil spring whereby axial extension and detention of said coil spring uniformly changes the shape of each of the helical coils and the diameter of the cylindrical coil as well as the distance between adjacent helical coils of the spring.

4. The variable attenuator as claimed in claim 3 in which said cylindrical drum is journaled in said other support portion and is rotatably adjustably mounted thereon, means for rotating the cylindrical drum and the cylindrical coil spring for imposing torque along the longitudinal axis of the cylindrical coil spring and adjustably winding the helical coils of the coil spring into an adjusted obturating relationship normal to the path of the radiated beam being attenuated.
